CLAIM

The ornamental design for a connector crimping tool, as shown and described.

DESCRIPTION

FIG. 1 is a perspective view of a connector crimping tool showing our new design;

FIG. 2 is a left side elevational view thereof, the opposite right side being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken lines showing of the crimping head is for illustrative purposes only and forms no part of the claimed design.

FIG. 1.

FIG. 2.FIG. 5.FIG. 3.FIG. 4.FIG. 6.
